The ornamental design for a seal protector and joint retainer for installation of front wheel drive assembly in a motor vehicle, as shown.

DESCRIPTION

FIG. 1 is a perspective view of a seal protector and joint retainer for installation of front wheel drive assembly in a motor vehicle showing our new design;

FIG. 2 is a top view thereof;

FIG. 3 is a front view thereof;

FIG. 4 is a rear view thereof;

FIG. 5 is a right side view thereof; and,

FIG. 6 is a left side view thereof.
